UNITED STATES PATENT OFFICE.

JOHN FRANCIS RANKEN AND ELLEN DAY RANKEN, OF NEW YORK, N. Y.

SANITARY REFUSE-BAG.

1,052,379.

Specification of Letters Patent. Patented Feb. 4, 1913.

Application filed February 18, 1910. Serial No. 544,579.

To all whom it may concern:

Be it known that we, JOHN F. RANKEN and ELLEN DAY RANKEN, citizens of the United States, and residents of the city of New York, borough of Brooklyn, in the county of Kings and State of New York, have invented a new and Improved Sanitary Refuse-Bag, of which the following is a full, clear, and exact description.

10 The object of the invention is to provide a new and improved sanitary refuse bag and holder for the same, more especially designed for receiving refuse in households, hospitals and other establishments, and arranged to provide a convenient and cheap means for receiving and bagging the refuse for ready transportation to a place of disposal.

For the purpose mentioned, use is made 20 of a bag provided at its mouth with an outwardly-extending annular fold, adapted to engage a supporting ring for suspending the bag and for holding the mouth thereof open for the reception of the refuse, the fold 25 being capable of being extended or drawn out to form a closing means for the bag after the same is filled.

A practical embodiment of the invention is represented in the accompanying drawings forming a part of this specification, in which similar characters of reference indicate corresponding parts in all the views.

Figure 1 is a perspective view of the sanitary refuse bag and holder for the same, part being broken out; Fig. 2 is an enlarged cross section of the same; Fig. 3 is a perspective view of a modified form of the support for the bag, parts being broken out; and Fig. 4 is a reduced perspective view of 40 the filled and closed bag.

The body A of the bag is provided at its mouth or upper end with an exterior double fold B, having an inner annular member B' and an outer annular member B², of which 45 the inner member B' forms an integral continuation of the bag body A and is folded outwardly and downwardly, to extend on the outside of the bag body A, and the outer member B² of the fold B forms an integral 50 continuation of the lower end of the inner member B' and extends upwardly on the outside of the said inner member to approximately the top thereof. A string or cord C is attached to the upper end of the bag body 55 A, with the ends at the outside thereof, for closing the mouth of the bag after the same

has been filled and as hereinafter more fully explained. A ring D for supporting the bag engages the bag body A exteriorly at the upper end thereof, directly under the junction of the fold member B' with the upper end of the bag body A, as plainly indicated in the drawings, so that the fold B hangs over the ring D. The ring D is preferably made of a piece of strong wire, bent 65 to form a ring, and a downwardly-extending twisted shank D', which extends between the inner member B' of the fold B and the outside of the bag body A, the shank D' terminating at its lower end in a hook D², extending upwardly outside of the fold B, to permit of conveniently engaging the hook D² with a socket, nail or other suitable support.

Located a distance above the floor, so as 75 to properly support the ring D and the bag A at the same time, the ring holds the mouth of the bag body open, to permit of conveniently placing the refuse into the bag body. When the bag body A has been filled with 80 the refuse, the fold B is drawn upward by the operator into extended position, so as to permit of conveniently disengaging the bag from the ring D and allowing closing 85 of the mouth of the bag by gathering the extended fold members B', B², as plainly indicated in Fig. 4, after which the gathered members are drawn together and tied with the string C, to securely close the bag to 90 prevent spilling of the contents. The filled and closed bag can now be readily carted away to a suitable place of disposal.

Instead of providing the hook D² for suspending the ring D and the bag, use is made of supporting rods E, connected at 95 their upper ends with a ring D³, engaging the bag at the upper end thereof under the fold B, as previously explained, the lower ends of the supporting rods E being attached to a ring E', preferably somewhat 100 larger than the bag supporting ring D³.

By the arrangement described, a supporting frame is provided which can be readily set up on a floor, to hold the bag body A suspended therein, with the bottom of the bag either resting on the floor or in a pan 105 F, into which the lower end of the supporting frame may be set, the said pan having retaining means F', preferably in the form of spring tongues or the like, for connecting the pan F with the lower end of the frame. It is understood that in this case 110

the sanitary refuse bag and the holder for the same are more particularly designed for holding heavier refuse, so that the bottom of the bag needs a support.

5 In practice, the bag A is preferably made of strong paper, and in case wet or moist refuse is to be disposed of then the bag is preferably made of waterproof paper or a like material.

10 The particular arrangement of the folds at the top of the bag, that is, with the upper edge of the outer fold member unconnected to the inner fold member, forms a finger pocket, by means of which the outer fold 15 may be grasped for the convenient drawing of the folded members upward without contact of the fingers with the inside of the bag.

Having thus described our invention, we 20 claim as new and desire to secure by Letters Patent:

A sanitary refuse bag, comprising a bag having an annular fold at its mouth, the fold being formed of an inner and outer

member, of which the inner member forms 25 an integral continuation of the bag body and is folded outwardly and downwardly to extend on the outside of the bag body, and the outer member of the fold forms an integral continuation of the lower end of 30 the inner fold member and extends upwardly on the outside of the inner member and with the upper edge of the said outer member unconnected to the inner fold member to form a finger pocket by means of 35 which the outer fold may be grasped for the convenient drawing of the folded members upward without contact of the fingers with the inside of the bag.

In testimony whereof we have signed our 40 names to this specification in the presence of two subscribing witnesses.

JOHN FRANCIS RANKEN.
ELLEN DAY RANKEN.
